UNITED STATES PATENT OFFICE.

EMANUEL SHENKAN, OF PITTSBURGH, PENNSYLVANIA.

ROTARY ERASER.

Application filed December 22, 1926. Serial No. 156,348.

My invention relates to an improvement in erasers, and while primarily intended for erasing incorrect single letters of typewritten words while the sheet of paper is in position in the typewriter, it will be obvious that the device may be successfully employed for any other erasing purposes wherein it is found to be applicable.

Important objects of the invention are to provide an eraser of the character described which is rotatably operable for facilitating the erasing of typewritten errors within the confines of a limited space without erasing adjacent matter, which is simple in its construction and arrangement, strong, durable and efficient in its use, compact conveniently operable, attractive in appearance and comparatively inexpensive to manufacture.

With the foregoing and other objects in view which will appear as the description proceeds, the invention resides in the combination and arrangement of parts and in the details of construction hereinafter described and claimed, it being understood that changes in the precise embodiment of the invention can be made within the scope of what is claimed without departing from the spirit of the invention.

In the drawing wherein like numerals of reference designate corresponding parts throughout the several views:—

Figure 1 is a side elevational view, partly in cross section, of a rotary eraser constructed in accordance with the invention.

Figure 2 is a bottom plan view of the bottom cap.

Referring in detail to the drawing 1 denotes an elongated, hollow, cylindrical barrel. The latter is provided with a cover cap 2 and a bottom cap 3, both of which have a detachable threaded connection with respective ends of the barrel 1. The bottom cap 3 is formed with an aperture 4 having four regularly arranged inwardly curved side walls 5, as clearly shown in Figure 2.

A spiral screw spindle 6 extends through the bottom cap aperture 4 and is provided with a cylindrical shank 7, which is fixed to the upper end thereof. The spindle 6 is preferably constructed from square stock which is twisted to provide a spiral screw conformation. When the spiral screw spindle 6 is shifted in either direction through the bottom cap aperture 4, by the reciprocation of the barrel 1, during the operation of the de-

vice, the contacting engagement of the aperture side walls 5 with the spindle 6 will impart a rotary movement to the latter in a manner well known in the art.

The spindle shank 7 is rotatably mounted in the barrel 1 and is longitudinally shiftable in the latter. The top of the shank 7 is formed with a pocket 8, which corresponds with a pocket 9 formed in the lower end of a longitudinally shiftable bearing slide 10 mounted in the barrel 1 above the shank 7. A bearing ball 11, facilitating the rotation of the spindle 6, is positioned in the barrel 1, and seats in the pockets 8 and 9 intermediate of the shank 7 and the bearing slide 10.

A spiral spring 12, having its upper end abutting against the cover cap 2 and having its lower end attached to the bearing slide 10, is mounted in the upper end portion of the barrel 1. The action of the spring 12 normally forces the spindle 6 to the extended position, as shown in Figure 1.

A split hollow stem 13, having an externally threaded upper end 14 and a tapering lower end 15, is fixedly carried at the lower end of the spindle 6. The eraser element 16, preferably soft rubber, is clamped in the stem 13, to project from the lower end 15 thereof, by means of a clamping sleeve 17. The upper end of the latter threadably engages the stem upper end 14 while the lower end thereof is correspondingly tapered and engages the lower tapered end 15 of the stem 13, for clamping the eraser element 16 in position. The release of the clamping sleeve 17 permits of the adjustment or replacement of the eraser element 16 in the stem 13.

In practice the operation of my improved eraser is as follows:—

Normally the spindle 6 is maintained in the projecting position by the action of the spring 12, as shown in Figure 1. The eraser element 16 is positioned to cover the surface to be erased. By forcing the barrel 1 downwardly, the spindle 6 and the associated eraser element 16, carried thereby, will be rotated to effect the erasing operation. The spindle 6 will now have entered the lower end portion of the barrel 1 and the spring 12 will be compressed. Upon releasing the pressure on the barrel 1, the action of the compressed spring 12 will force the spindle 6 to the projecting position, meantime rotating the eraser element 16 for containing the erasing operation. The reciprocation of the barrel 110

1 is continued, in the manner stated, until the erasing is completed. The action of the spring 12, during the operation of the device will provide suitable pressure for efficiently effecting the erasing operation.

What I claim is:

In combination, a rotary eraser, of the character described comprising an elongated hollow barrel provided with a bottom cap, 10 said bottom cap formed with an aperture having four regularly arranged inwardly curved side walls, a spirally twisted spindle extending through said bottom cap aperture and

shiftable in either direction in the latter to impart rotary movement to said spindle, a bearing slide mounted in said barrel, a shank fixed to the inner end of said spindle and disposed in said barrel, a bearing ball disposed between the adjacent ends of said slide and said shank, a spring mounted in said barrel and engaging said bearing slide for normally projecting said spindle from said barrel, and an erasing element adjustably connected to the lower end of said spindle.

In testimony whereof I affix my signature,

EMANUEL SHENKAN.
